PROPELLION CONTROL FOR OUTBOARD
MOTOR BOATS

Paul R. Reid, Madill, Okla.

Application August 11, 1947, Serial No. 768,015

9 Claims. (Cl. 114—145)

1

This invention relates to propulsion means for boats equipped with outboard motors and is preferably designed as an attachment to the motor for controlling the speed of the boat in both forward and reverse directions without changing the speed of the motor, being advantageously employed in approaching or leaving a wharf or mooring, or when trolling for fish at different desired boat speeds.

The main object of this invention is to provide a propulsion control including a guide or deflector to receive the column of water as it is delivered by the propeller, reverse its course of flow and direct it forwardly and downwardly to regulate the forward motion of the boat or to drive the same in reverse direction.

Another object of this invention is to provide the guide or deflector with one or more internal baffles or division plates, to more efficiently reverse the direction of flow of the column of projected water and prevent as much as possible any loss of power caused by the reversal of flow.

Still another object of this invention is to provide a guide or deflector as an attachment to outboard motors, having a suitable supporting structure including linkage and lever mechanism whereby the guide or deflector may be raised to an inactive position, out of the water, or lowered into the water to different active positions adjacent to the propeller, which is relatively simple in construction, inexpensive to manufacture and may be readily attached to the standard type of outboard motors.

A further object of this invention is to provide a propulsion control guide or deflector which may be lowered into the water to act purely as a braking means for the forward motion of the boat, as when approaching a landing, or adjusted to different vertical positions in the water with reference to the propeller to obtain different boat speeds in either forward or reverse directions, with means included in the supporting structure and lever mechanism to releasably and yieldably retain said guide or deflector in its adjusted position.

Still further objects are: To provide a holding means, preferably in the form of a cable or the like, for retaining the outboard motor and its associated control means in a full operative position and prevent any tendency of the same to swing in a backwardly and upwardly direction away from the boat; to provide cooperating yielding clutch members as parts of the guide or deflector support and control lever; to pro-

2

vide said control with a slip clutch yielding under abnormal conditions, including a plurality of plates held in frictional contact with each other by means of suitable cam and spring means, the spring being selected or mounted for tension adjustment according to the frictional pressure desired to be applied to the clutch parts.

With these and other objects in view there has been illustrated, in the accompanying drawings, the preferred forms of this invention.

In the drawings:

Figure 1 is a side view showing the control means attached to a standard type of outboard motor.

15 Figure 2 is a rear view of the same.

Figure 3 is a sectional view taken on the line 3—3 of Figure 1.

Figure 4 is a sectional view taken on the line 4—4 of Figure 2.

20 Figure 5 is a sectional view taken on the line 5—5 of Figure 1, illustrating the pivotal connection between the guide arm and an attaching clamp.

Figure 6 is a front view of the preferred form 25 of the guide or deflector.

Figure 7 is a sectional view taken on the line 7—7 of Figure 6.

Figure 8 is a view looking upwardly at the discharge end of the guide or deflector.

30 Figure 9 is a transverse sectional view of the top plate of the guide or deflector taken on the line 9—9 of Figure 7.

Figure 10 is a transverse sectional view of the top plate of the guide or deflector taken on the line 10—10 of Figure 7.

35 Figure 11 is a side view similar to Figure 1 illustrating the control structure from the opposite side.

Figure 12 is a vertical sectional view of the 40 clutch for retaining the guide or deflector in adjusted positions.

Figure 13 is a side elevation of the clutch.

Figure 14 is a perspective view of the cam employed for causing frictional engagement of the 45 clutch plates.

Figure 15 is a perspective view of a modified form of the guide or deflector.

Figure 16 is a front view of the modified form of guide or deflector illustrated in Figure 15.

50 Figure 17 is a sectional view taken on the line 17—17 of Figure 16.

Figure 18 is a rear view of the modified guide.

Figure 19 is a bottom view of the guide shown in Figure 15 disclosing the discharge outlet.

55 Figure 20 is a sectional view taken on the line

A—A through the top wall of the guide shown in Figure 17.

Figure 21 is a similar view taken on the line B—B of Figure 17.

Figure 22 is another view similar to Figures 20 and 21 taken on the line C—C of Figure 17.

Referring to the drawings wherein like reference characters designate similar parts throughout the different views, 14 indicates a standard type of outboard motor which is secured to the boat by means of a bracket 15 and a pivoted sleeve 16, permitting both vertical and horizontal pivotal movements of the motor.

Detachably secured to the motor 14 is a support 17, for mounting the guide or deflector 18 to said motor in a manner as to be adjusted vertically in-and-out of the water and comprises in part the links 19, 20 and 21. The link 19 is secured to a two-part clamp 22 which is shaped to conform with that portion of the outboard motor around which it is placed. The upper links 20 and 21 are connected at one end to link 19 by means of a shaft 23 and are secured to the motor casing at their other end through the medium of screws 24, these links also act as bearings for the shaft 23. In order to provide the necessary rigidity to the supporting links 19, 20 and 21, so far described, a brace 25 is secured to an edge of the link 21, as at 26, and extends in an upwardly and forwardly direction to be attached to the motor casing by a screw in the same manner as links 20 and 21.

Attached to the guide or deflector, as by welding or otherwise, is the rod or bar 27 which may be of various forms, but here shown as of angular shape. The bar is directly secured to the guide or deflector at its outer end but to properly position the guide and give rigidity to the connection, a spacing block is employed as indicated at 27'. In order that the guide may be swung vertically in-and-out of the water, the bar 27 is pivotally connected to the clamp bolt 28 having its ends provided with spaced ears 29 for this purpose, as clearly shown in Figure 5.

Spaced somewhat from the inner end of the bar 27 is secured, as by welding, an extension 30 having its lower end bifurcated as at 31 to straddle the fin 32, of the motor casing. This construction is provided as a means to steady or lend rigidity to the control, while in operation, and eliminates any possible tendency of the guide vibrating when passing through the water.

The bar 27 is further provided with ears 33, forming means for pivotally connecting the operating link 34 thereto, as by a suitable bolt 35. The shaft 23, which is rotatably mounted in the ends of the links 19, 20 and 21 has attached thereto an operating lever 36, including parts of a slip clutch 37 designed to hold the guide or deflector in adjusted position under normal operations, but will yield under abnormal conditions. The specific details of this clutch will be later described.

Also carried by the shaft 23 is a lever 38, having a hub 39, and a set screw 40 for securely fastening the lever to the shaft 23, this lever having connection with the operating links 34. It will be seen that when the lever 36 is swung vertically from its full line position, as shown in Figure 1, it will effect a corresponding movement of the guide or deflector 18, as clearly shown in dotted lines of this figure, through the medium of the shaft 23 to which the lever 36 is connected, lever 38, the operating links 34 and the bar 27 attached to the guide. Any intermediate position

of the guide or deflector may be selected according to the type of propulsion desired. When the guide or deflector is lowered into the water and not in the path of the column of the water discharged by the propeller, it merely acts to brake or retard the forward movement of the boat. As the guide is lowered to different positions with relation to the column of water directed rearwardly by the propeller varied forward drives of the boat may be accomplished for landing purposes or, as when trolling for fish. As the guide approaches or reaches its lowermost position varied drives of the boat in reverse are obtained.

In the present invention, the guide or deflector 18 is provided with an entrance opening directed toward the propeller to receive the water driven rearwardly thereby and an outlet opening designed to deliver the water in a column and cause it to be directed in a forwardly and downwardly direction. The guide is so proportioned as to cause the projected column of water to be delivered below the working area of the propeller and at a point remote therefrom to obtain full effect power from the projected stream.

The preferred form of the guide or deflector 18 is disclosed in Figures 6 to 10 inclusive wherein the same embodies a top wall 41, rear wall 42 and side walls 43, providing a forward entrance opening 44 and a bottom delivery opening 45. It will be noted in Figure 7 that the top and rear walls 41 and 42, which are fashioned from a single sheet of metal, are curved longitudinally as an approximate arc of an oval, the curvature of the walls gradually increasing from the forward edge of the top wall to the lower edge of the rear wall to properly conduct the water rearwardly some distance and reverse its direction of flow to be delivered at a point distant from the propeller and directed in a downwardly and forwardly direction. The rear wall 42 is straight transversely, as shown in Figure 8, while the top wall 41 is curved transversely in varying degrees beginning at the forward end as approximately semi-circular (Figure 6) and diminishing in curvature rearwardly as shown in Figures 9 and 10, until the same merges with the rear wall where it is also straight.

The side walls 43 are connected to the edges of the top wall 41 and the edges of the rear wall 42. As will be seen in Figures 6 and 8, the rear wall 42 is of less width at its lower edge than at the point where it merges with the top wall 41, which provides a construction wherein the side walls converge both downwardly and rearwardly. The bottom opening 45 is approximately rectangular in form and has a discharge area equal to or greater than that of the entrance opening 44 to prevent any tendency of pressure building up within the guide.

Attached to the side walls 43 are the baffles 46 and 47 extending varying degrees within the guide and terminating at their lower edges in line with the angular edge 43' and the horizontally disposed edges 43'' of the side plates 43, forming channels 48 and 49 through which the water flows in a reverse direction as delivered by the propeller and directed in a forwardly and downwardly direction. The channels 48, formed by the baffles 46, are designed to take care of all of the water delivered to the guide, but in the event that pressure should build up within these channels 48, channel 49, formed by baffle 47, will act as a bleed opening to prevent any water from being projected laterally and not entering the guide. To facilitate, and aid the entry of water

in the guide, as projected by the propeller, the forward edge of the guide may be slightly flared at 50, which will also strengthen the structure at this point. Further reinforcements may be added to the guide as seen fit, such as the angular brace 50', or the flange 51.

It will be noted that the water delivered from the propeller in a column of general cylindrical form is received in the entrance opening 44 of the guide and gradually reformed, reversed and projected at the outlet opening 45, as a column which is approximately rectangular in cross section. It will be further noted that as the column of water reaches the outlet opening its direction of delivery will not only move the boat in a rearwardly direction, but in addition will act to elevate the stern of the boat so that its movement will be freer through the water due to less resistance offered.

This form of guide is very efficient, especially when driving a boat in reverse direction, as the same is of a shape and length to properly receive and deliver the column of water in a downwardly and forwardly direction. As the side plates 43 converge toward the rear, and the rear wall 42 is of small area, there is produced a guide which is more-or-less pointed offering very little resistance as it passes rearwardly through the water.

In Figures 15 to 22 there is disclosed a modification of the present invention dealing with the guide or deflector, which takes on a slightly different form, but functions in the same manner as the guide illustrated in Figures 6 to 10. In this modified form the guide or deflector 52 is of general sector formation, having its top and rear walls 53 and 54 also fashioned from a single sheet of metal, but curved longitudinally as an arc of a circle shown clearly in Figure 17 of the drawing. The rear wall 54 is straight transversely, as shown in Figure 19, while the top wall 53 is curved transversely in varying degrees beginning at the forward end as semi-circular (Figures 15 and 16) and terminating in curvature rearwardly as shown in Figures 20 and 21 until the same merges with the rear wall 54 where it is also straight (Figure 22).

Secured to the edges of the top and rear walls 53 and 54, are the side plates 55 to which are fastened the baffles 56 and 57 for causing a curved and reverse flow of the column of water in the same general manner as in the guide of the preferred form. These baffles extend into the guide to different degrees to carry the water and redirect the same through the outlet opening 58, the lower edges of the baffles terminate at the lower edges 59 of the side plates 55.

As will be seen the forward edge of the guide or deflector 52 is slightly flared at 60 to facilitate the entrance of the delivered water column. The channels 61, formed by the baffles 56, are designed to take care of all of the water delivered to the guide or deflector, but in the event that pressure should build up within the guide or deflector the passages 62, formed by the baffles 57 will act as bleed openings to prevent any water from being projected laterally and not entering the guide.

As will be seen in Figures 16, 18 and 19 the rear wall 54 is of less width at its lower edge than at the point where it merges with the top wall 53 and that the side plates 55 converge toward the lowest point of the guide, as clearly seen in Figure 19, presenting a somewhat narrow rear wall which offers less resistance as the guide passes backward through the water.

It will be noted that the water delivered from the propeller in a column of general cylindrical form is received in the entrance opening 63 of the guide or deflector and gradually reformed and reversed to be projected at the outlet opening 56, as a column which is either rectangular or square in cross-section. It is also true in this form that the water discharged from this guide will act to elevate the stern of the boat.

In order that the motor and its associated propulsion control may be held fixed at times to prevent any tendency of the same to swing rearwardly and upwardly, a lever 64 is secured to the shaft 23 and is perforated at 65 to receive a cable 67, which passes around a pin 68, carried by the bracket 15, and is finally secured to the pivot sleeve 16 at 69. When the lever 36 is in its lowermost position the cable 67 is held taut which will prevent the motor and control mechanism from moving away from the bracket 15, on the other hand movement of the motor is permitted when the lever 36 is in a raised position providing a slack in the cable, as indicated at 70.

As is generally known, outboard motor boats are used for fishing and trips around pleasure resorts, and on numerous occasions these boats are required to run in shallow water where submerged objects are present, as rocks, etc., and in order to protect the present control mechanism from damage there has been included in this construction a safety element in the form of a slip clutch 37 for holding the guide or deflector in its adjusted position under normal operation, but will yield when an obstruction is encountered, to permit the guide to raise and ride over the same, this clutch being associated with the operating lever of the control and its support, the latter including the clamp 22, links 19, 20 and 21 and bracing arm 25.

As will be seen, on referring to Figures 12 and 13, this clutch is of the friction plate type embodying the fixed friction plates 71, shown as of semi-circular form (Figure 13) and the movable friction plates 72 and 73 carried by the lever 36. The fixed plates 71 are supported in vertical position by the arms 74 to which they are rigidly attached. Due to the fact that one plate is secured to each side of the supporting arms 74, acting as spacers, these plates are properly separated to receive the movable plate 73 therebetween, the other movable plate 72 assuming a position adjacent to one of the fixed plates and acting additionally as an abutment during clutch-applying operation. The arm 74 may be formed as an integral part of the link 21, or welded or otherwise secured thereto, as found most practical in manufacture. In order to properly position the fixed friction plates with reference to the movable plates, the arms 74 are bent at 75 to place the ends thereof out of plane with the link 21, or otherwise fashioned to accomplish the same result.

The lever 36, which is secured to shaft 23, is provided with inwardly directed ears 76 for pivotally supporting a camming lever 77, being also equipped with ears 78 by which it is connected to the ears of the lever 36 by means of a bolt or pin 79.

This cam lever 77 is preferably of U-formation including the arms 80 and a bridging plate 81, functioning as a friction plate and a camming pressure applying means. As the normal operation of the clutch is in applied position a spring 82 is provided to swing the camming lever 77 into clutch-applying position. This spring may be

selected to apply the appropriate pull on the camming lever or so mounted as to have its tension adjusted. As shown in Figures 12 and 13 this spring is equipped with hooks at each end to be connected at one end in a hole 83 of the lever 36, and a hole 84 of the plate 85 carried by the connecting bolt or pin 86 of the camming lever. It will be seen that as the spring 82 is connected to the lever 36 at one end, and to the camming lever 11 at the other end, there exists a constant pull on the camming lever, swinging the same in a direction as to cause the bridging plate 81 to move or press the various friction plates 11, 12 and 13 into engagement with each other and with a degree of pressure determined by the spring tension employed. When adjusting the control to different operative positions, or an inactive position out of the water, the clutch is released and in order to accomplish this result a clutch-releasing lever 87, carried by the lever 36, is employed, having connection with the camming lever through the medium of the rod 89 attached at its lower end to the camming lever as by the bolt or pin 86. Operation of this lever 87 will withdraw the camming lever against the pull of the spring, permitting the friction plates to separate and allow free adjustment of the guide or deflector as desired.

It is understood that minor changes may be made to the control means of this invention without departing from the scope of the appended claims.

I claim:

1. A propulsion control attachment for an outboard motor including a screw propeller, comprising a guide of general sector shape having a top wall, a rear wall and plain side walls, said top wall and rear wall being longitudinally curved as an arc of an oval, said top wall being curved transversely, said rear wall being straight transversely, the degree of transverse curvature of the top wall decreasing from the forward edge thereof until it merges with the rear wall, said guide having a front entrance opening and a bottom outlet opening, and means attached to said motor for adjustably supporting said guide.

2. A propulsion control attachment for an outboard motor including a screw propeller, comprising a guide having a top wall, a rear wall, and plain side walls, the top and rear walls being longitudinally curved as an arc of an oval, said guide having an entrance opening and a bottom outlet opening and adjustably positioned to the rear of the propeller to direct the column of water delivered thereto by the propeller in a forwardly and downwardly direction and beneath said propeller, baffle plates extending different degrees within the guide dividing the column of water into separate streams at the point where reverse flow is initiated and secured to the side walls, and means for adjusting said guide vertically with reference to said propeller.

3. A propulsion control attachment for an outboard motor including a screw propeller, comprising a guide positioned to the rear of the propeller to direct the column of water delivered thereto by the propeller in a forwardly and downwardly direction and beneath said propeller, means for attaching the guide to said motor, and a lever mechanism carried by said attaching means connected to said guide for adjusting the same vertically, said lever means including a slip clutch.

4. A propulsion control attachment for an outboard motor including a screw propeller, com-

prising a guide to be positioned to the rear of the propeller having curved top and rear walls and plain side walls for directing a column of water forwardly and downwardly and beneath said propeller, a support for the guide attached to the motor, a lever operatively connected to the guide and a slip clutch for holding the lever in adjusted position, said clutch comprising fixed and movable plates, and means for causing frictional engagement of said plates.

5. A propulsion control attachment for an outboard motor including a screw propeller, comprising a guide adjustably positioned to the rear of the propeller having curved top and rear walls and plain side walls for directing a column of water forwardly and downwardly and beneath said propeller, a support for the guide attached to the motor, a lever operatively connected to the guide and a slip clutch for holding the lever in adjusted position, said clutch comprising fixed plates carried by the support, movable plates secured to said lever and a spring-operated camming lever to normally hold said plates in frictional engagement.

10 6. A propulsion control attachment for an outboard motor including a screw propeller, comprising a guide adjustably positioned to the rear of the propeller having curved top and rear walls and plain side walls for directing a column of water forwardly and downwardly and beneath said propeller, a support for the guide attached to the motor, a lever operatively connected to the guide and a slip clutch for holding the lever in adjusted position, said clutch comprising fixed 15 plates carried by the support, movable plates secured to said lever and a spring-operated camming lever to normally hold said plates in frictional engagement.

20 7. A propulsion control attachment for an outboard motor including a screw propeller, comprising a guide adjustably positioned to the rear of the propeller having curved top and rear walls and plain side walls for directing a column of water forwardly and downwardly and beneath said propeller, a support for the guide attached to the motor, a lever operatively connected to the guide and a slip clutch for holding the lever in adjusted position, said clutch comprising fixed 25 plates carried by the support, movable plate segments secured to said lever, a spring-operated camming lever to normally hold said plates in frictional engagement, and means for releasing said clutch.

30 8. A propulsion control attachment for an outboard motor including a screw propeller, comprising a guide to be positioned to the rear of the propeller having curved top and rear walls and plain downwardly and rearwardly converging side walls for directing a column of water forwardly and downwardly and beneath the propeller, and a support for the guide attached to the motor comprising a bar extending longitudinally of the motor, attaching plates at each end of the bar for securing the same to the motor, an arm having one of its ends pivotally connected to the bar and its other end attached to the guide, and a lever mechanism pivotally associated with the bar having link connection with the arm 45 whereby operation of the lever mechanism will raise or lower the guide.

40 9. A propulsion control attachment for an outboard motor including a screw propeller, comprising a guide to be positioned to the rear of the propeller having curved top and rear walls and plain downwardly and rearwardly converging side walls for directing a column of water forwardly and downwardly and beneath the propeller, and a support for the guide attached to the motor comprising a bar extending longitudinally of the motor, attaching plates at each end of the bar for securing the same to the motor, an arm having one of its ends pivotally connected to the bar and its other end attached to the guide, and a lever mechanism pivotally associated with the bar having link connection with the arm whereby operation of the lever mechanism will raise or lower the guide, said arm being provided with a bifurcated extension engageable with

the motor when the guide is in its lowermost position to prevent lateral movement of the guide.

9. A propulsion control attachment for an outboard motor including a screw propeller comprising a guide of general sector shape to be positioned to the rear of the propeller having a top wall, a rear wall and side walls, said guide also having a front entrance opening and a downwardly directed discharge opening, the top and rear walls being longitudinally curved as an arc of an oval, the top wall being curved transversely, the rear wall being straight transversely, the degree of transverse curvature of the top wall decreasing from the forward edge thereof until it merges with the rear wall, the side walls being plain and converging downwardly and rearwardly, and a support for the guide attached to the motor comprising a bar extending longitudinally of the motor, attaching plates at each end of the bar for securing the same to the motor, an arm having one of its ends pivotally connected to the bar and its other end attached to the guide, and lever mechanism pivotally associated with the bar having link connection with the arm whereby operation of the lever mechanism 25 will raise and lower the guide.
